UNITED STATES PATENT OFFICE.

ENOCH WHALLEY, OF WILLIMANSETT, MASSACHUSETTS.

TRUCK.

1,194,105.

Specification of Letters Patent. Patented Aug. 8, 1916

Application filed October 7, 1915. Serial No. 54,665.

To all whom it may concern:

Be it known that I, ENOCH WHALLEY, a citizen of the United States of America, residing at Willimansett, in the county of 5 Hampden and State of Massachusetts, have invented a new and useful Truck, of which the following is a specification.

My invention relates to improvements in trucks, and more especially to trucks of the 10 so-called elevating type, or those wherein a horizontal movement is converted into a vertical movement, for use in factories, warehouses, stores, and other places to haul goods or materials from one point to another by 15 hand, and said invention resides in a certain peculiar construction of the two truck sections and the separating mechanism, movable supports, or raising and lowering elements thereof, and in certain peculiar 20 tongue-controlled means, together with such auxiliary and subsidiary parts and members as may be necessary or desirable to render the invention practicable, all as hereinafter set forth.

The primary object of my invention is to produce a comparatively simple and inexpensive, but strong and durable, easily operated, and highly efficient elevating truck, for use in raising goods or material from 25 the support therefor, or with such support, from the floor, hauling said goods or material to the desired place, and there lowering and depositing the same. In this truck the amount of friction is reduced to the 30 minimum, hence comparatively little effort is required on the part of the operator in order to raise a very heavy load.

A further object is to provide such a truck with means whereby the operation 35 and manipulation of the truck and load, through the medium of the handle or tongue, are facilitated in a marked degree, and this without complicated mechanism. The tongue-controlling and tongue-operated 40 means employed in this truck are, in fact, very simple and consist of few parts, the same being true of the truck as a whole.

Still another object is to afford means for utilizing the tongue for unlocking and releasing the load, although the simple latch lock, which I prefer to employ, and which, is automatic in action so far as securing the 45 load in elevated position is concerned, can be unfastened without the aid of said tongue.

The truck, while itself light in weight, is 50 capable of handling a load of great weight;

and said truck, although having an adequate range of elevation, is sufficiently low, when the upper section is depressed, to be operated in connection with a stack of goods or material that is supported very close to the 60 floor, which is obviously an essential feature in most cases.

Other objects and advantages will appear in the course of the following description. 65

I attain the objects and secure the advantages of my invention by the means illustrated in the accompanying drawings, in which—

Figure 1 is a top plan of a truck which 70 embodies a practical form of my invention, the upper section being depressed and a portion of the handle or tongue broken out; Fig. 2, a sectional detail taken on lines 2—2, 75 looking in the direction of the associated arrow, in Fig. 1, showing the locking member in engaging position, as when said upper section is elevated; Fig. 3, a front elevation of said truck, with said upper section elevated and illustrating the operation of 80 the mechanical unlocking or releasing mechanism, the major portion of said tongue being broken off in this and the next view; Fig. 4, a side elevation of said truck, with 85 the parts displaced as in the first view, and, Fig. 5, a longitudinal vertical section, on lines 5—5, looking in the direction of the associated arrow, Fig. 1, said upper section being here in elevated position and a portion 90 of said tongue broken out.

Similar numerals refer to similar parts throughout the several views.

This truck comprises an under section, body, or carriage mounted on rolls or wheels, a superimposed or upper section or 95 platform arranged to move longitudinally or horizontally and vertically relative to said carriage, inclined bearing members on said sections and interposed free revoluble members constituting the movable supports 100 for said upper section or platform and the direct means whereby said platform is raised and lowered, actuating means for drawing said platform forward on said carriage or forcing the latter backward under the 105 former, as the case may be, to elevate said platform, a tongue which is adapted to be interlocked with and disengaged from said actuating means, and with which the truck is moved about and said platform-actuating 110 means operated to elevate said platform, the arrangement of parts being such that said

tongue, when disengaged from said actuating means, is entirely free for use solely as a handle for moving the truck in any direction, an automatic lock for said platform 5 when elevated, and a knock-off carried by said tongue for said truck.

Although I have illustrated in the drawings and will next proceed to describe in detail a truck which embodies in a practical 10 form the essential features of the invention, it is to be understood that numerous departures in the shape, size, construction, and arrangement of some or all of the parts of the truck as thus presented may be made 15 without violating the spirit of said invention.

The body or carriage consists of two side pieces 1 connected at their front ends by a cross piece 3 and a little distance from 20 their rear ends by a cross piece 4. The side pieces 1 are provided at their front ends on top with lugs or stops 6—6 and at their rear ends on top with lugs or stops 7—7, and have intermediate parallel ribs 25 8—8, the latter inclining downwardly from front to back, and in the present case being located on the outer faces of said side pieces. An upward incline is given the forward terminal portions of the side pieces 1 and a 30 pair of inclined top surfaces or bearings 9 is obtained, and a downward incline is given the upper edges of the rear terminal portions of said side pieces to form a second pair of inclined top surfaces or bearings 10. 35 The angles of all of the bearings 9 and 10 are of the same degree. An inclined rack 11 is located on each side piece 1 adjacent to each of the bearings 9 and 10 of said side piece, the two racks having the same angle 40 in degree as said bearings, and in this instance being made up of a series of pins which pins project inwardly from said side piece below said bearings. A substantial lug 12 projects forwardly from the center 45 of the cross piece 3, and two trunnions 13 extend from the ends of the cross piece 4 and through the side pieces 1 to receive a pair of rear wheels 14. The stops 7 are at 50 the lower rear ends of the bearings 10 and immediately adjacent to the corresponding ends of the back racks 11, and there are shoulders, at the lower rear ends of the bearings 9, which form stops 15 that are immediately adjacent to the corresponding ends 55 of the front racks 11.

The wheels 14 support the rear end of the carriage, and the front end of said carriage is supported by a swivel 16 and a wheel 17, the lug 12 resting directly on said swivel 60 and the latter having a vertical pivot pin 18 that passes upwardly into and through said lug. The pivot pin 18 is held in place in the lug 12 by means of a horizontal lock pin 19 which extends through and projects 65 from said pivot pin above said lug. The

wheel 17 is mounted between lugs 20 which form parts of the swivel 16 and on an axle 21 that is journaled in or supported by said lugs. Projecting forwardly from the swivel 16 at the top are two more lugs 22 having a 70 pin 23 at their front ends.

An angular lifter 24 is mounted at one end to swing on the pin 23, and with the opposite end normally directed upwardly or rearwardly, according to the position of said lifter. The lifter 24 has a tongue-engaging part formed by a recess or notch 25 therein in line with the longitudinal center of the branch or arm thereof that is mounted on the pin 23, said notch opening through the 75 edge of said lifter at the outer end of said center. A tongue 26 is also mounted at its inner end to swing on the pin 23 and has provision for longitudinal movement thereon as well, such provision being made by laterally slotting said inner end, as indicated at 27. The tongue 26 has a lifter-engaging part in the form of a lug or tooth 29. The inner terminal portion of the tongue 26 is longitudinally and vertically slotted at 29 to 80 receive the lifter 24 in part, and the tongue 28 is at the closed end of the slot in position to enter the notch 25, when said tongue is manipulated to effect such entrance.

In order to engage the tongue 26 with the lifter 24, it is usual to draw the former forward on the pin 23 as far as the slots 27 will permit, or into the position which the tongue occupies while being used to haul the truck about, swing said tongue upwardly and rearwardly until the tooth 28 is in line with the notch 25, and lower said tongue with said tooth in said notch. The lifter 24 can now be rocked on the pin 23 with and by means of the tongue 26. The tongue is disengaged from the lifter simply by actuating the former longitudinally to withdraw the tooth 28 from the notch 25, and then said tongue can be employed like an ordinary truck tongue, except for the movement occasioned by the presence of the slots 27, as when the tongue with its tooth clear of the lifter is used to back the truck after it has been used to haul the same forward, and vice versa. The tongue is provided at its free end with 90 a cross-bar or handle 30.

The platform consists of two side pieces 31 connected at their rear ends by a cross piece 32 and a little distance from their front ends by a cross piece 33. The cross piece 32 is flush at the top with the tops of the side pieces 31 and extends beyond the latter, while the cross piece 33 is depressed. Lugs 34—34 are let into and secured to the side pieces 31, with their upper surfaces flush with the top surfaces of said side pieces, to increase the bearing surface for the load, which surface comprises the upper surfaces of said side pieces, lugs, and the cross piece 32. The lugs 34 extend outwardly and may 100

be in line with the cross piece 33. Lugs are provided at the front ends on top of the side pieces 31 to form stops 35 for the load, and such lugs extend downward and forward to form stops 36 for the platform. The stops 6 are in the paths of travel of the stops 36 and contact with the latter when the unloaded platform is actuated forward on the carriage, or said stops 6 contact with said stops 36 when said carriage is forced back under the platform while in the act of raising the load, according to circumstances. The aforesaid lugs also afford at their rear under sides stops 37 which coöperate with the stops 15 in the manner presently to be described. It is understood, of course, that the side pieces 31 are arranged directly over the side pieces 1. A short distance from the rear ends of the said pieces 31 on the bottoms of the same are shoulders which form stops 38, and these coöperate with the stops 7 in the manner presently to be described. An upward incline is given the under edges at the front terminal portions of the side pieces 31 to form a pair of inclined bottom surfaces or bearings 39, the stops 37 being at the forward and upper ends of such bearings, and a downward incline is given the under edges of the rear terminal portions of said side pieces to form a second pair of inclined bottom surfaces or bearings 40, the stops 38 being at the forward and upper ends of said last-mentioned bearings. The angles of all of the bearings 39 and 40 are of the same degree, and such degree is the same as that of the angles of the bearings 9 and 10. An inclined rack 41, similar to the racks 11, is located on each side piece 31 adjacent to each of the bearings 39 and 40 of said side piece, the two racks 41 having the same angle in degree as said bearings and said racks 11. The stops 37 are adjacent to the front ends of the forward racks 41, and the stops 38 are adjacent to the front ends of the rear racks 41.

Between each pair of under and over parallel bearings, 9 and 39 and 10 and 40, is one end of one of a pair of transverse shafts 42, and secured to each of such shafts between each pair of under and over parallel racks 11 and 41 and intermeshing therewith is a pinion 43. The bearing ends or terminals of the shafts 42 are of such diameter that the platform is supported at an elevation which enables the stops 36 and 37 and the stop 38 to clear the bearings 9 and 10, and the bearings 39 and 40 to clear the stops 15 and 7, as said platform or the carriage is moved the one relative to the other. The shafts 42 afford or serve as roller bearings for the two truck sections, and such bearings or shafts are held in place, steadied, and controlled by their pinions 43 and the racks 11 and 41. More or less than the number of racks and pinions shown may be used.

Assuming that the platform be drawn for-

ward on the carriage, it is clear that the roller bearings afforded by the shafts 42 roll on the carriage bearings 9 and 10 and the platform bearings 39 and 40 ride on said roller bearings, and that the pinions 43 travel on the carriage racks 11 while the platform racks 41 travel on and are the actuating or power-transmitting mediums for said pinions, all movements being forward and upward. Assuming that the platform be moved or permitted to move backward on the carriage, it is equally clear that the same members are brought into play, only this time in a reverse direction, to the end that said platform is lowered, when in the first case it was elevated. When the platform is retracted to lower it, the bearing parts of the shafts 42 encounter at the end of their travel the stops 15 and 7 and at the same time the stops 37 and 38 encounter said bearing parts, thus positively checking and securely holding said platform.

An arm 44 projects forward from the center of the cross piece 33, and a flexible connection, as a chain 45, extends between the front end of said arm and the free end of the lifter 24. The chain 45 should be long enough to permit whatever lost motion or play may be needed. It is the act of rocking the lifter 24 on the pin 23 forward and downward, from the position which it occupies in Figs. 1 and 4, that causes the platform to be drawn forward, or the carriage to be forced backward, and said platform consequently to be raised, said lifter operating through the chain 45 and the arm 44.

A spring latch 46 having a head 47 extends forward from the cross piece 33 with said head in position to snap over and engage the front edge at the top of the cross piece 3, when the platform is in its forward and elevated position, and as shown in Fig. 2, for the purpose of holding said platform in such position. The latch head 47 engages the cross piece 3 at the time the stops 36 encounter the stop 6, or vice versa. The latch head 47 may be forced upward out of engagement with the cross piece 3 either by means of the foot of the operator, or through the medium of a dog 48 on the tongue 26. The dog 48 projects from the tongue 26 beyond the upper or inner edge thereof, and is so located thereon as to enable the protruding terminal of said dog to be introduced beneath the outer protruding end of the latch head 47, when said tongue is held in an approximately upright position and the swivel is swung quarter way around on the latch side of the longitudinal center of the truck, as shown in Fig. 3. With the dog 48 under the head 47 the latter is forced upwardly by rocking the tongue 26 outwardly. The head 47 has just been raised clear of the cross piece 3, in Fig. 3, as at the instant of descent of the platform. The tongue is usually in

terlocked with the lifter 24 when used to release the latch 46, although this is not necessary. The chain 45 is of such length that the release of the latch can safely be effected by means of the tongue while interlocked with the lifter.

Vertical arms 49-49 are secured to the exterior sides of the side pieces 31, extend down outside of the ribs 8, and have inwardly directed inclined extensions 50-50 which enter and slide beneath said ribs. The purpose of the arms 49 with their extensions 50 is to prevent the platform from being lifted away from the carriage or tilted laterally thereon, and generally to steady said platform. The extensions 50 are always beneath the ribs 8 regardless of the relative positions of the upper and under truck sections.

20 Lugs 51 may be provided on the inside of the side pieces 1 for the cross piece 4, on both the inside and outside of the side pieces 31 for the cross piece 32, and on the inside of said side pieces 31 for the cross piece 33, said cross pieces being mounted on and secured to said lugs.

The pile or stack of goods or material to be handled with my truck is supported from the floor at a sufficient height to enable said truck to be backed under the same while the platform is depressed, and ordinarily portable benches are provided to support such goods or material, such benches being raised, transported, and set down again with the goods or material on them during the entire time.

Briefly the operation of the truck as a whole is described as follows, starting with the parts disposed as in Figs. 1 and 4. The 40 truck is hauled by the tongue 26 to the vicinity of the load to be moved and backed beneath the same. Then the tongue is swung up and caused to interlock with the lifter 24, and forced forward and downward to raise the load, which includes the bench when present, from the floor, on or with the platform, through the medium of said lifter, the chain 45, and the arm 44, the roller bearings or shafts 42, which intervene between the 45 carriage and platform, rendering this operation easy of accomplishment. As soon as the platform is raised to the full extent it is secured by the latch 46 in the manner previously explained—see Figs. 2 and 5. Next 50 the truck with its load is hauled by means of the tongue to the desired locality, being steered without difficulty or being hampered in any way by the lifting mechanism, because said tongue moves out of locking engagement with the lifter 24 as soon as the tongue is pulled forward for hauling purposes. And, finally, the load is deposited by throwing up the latch 46 in either of the 55 ways hereinbefore described and thus permitting the platform to descend until the

bench rests again on the floor, or the load in the absence of the bench rests upon other supporting means, when the truck is drawn from beneath the load and out of the way. In the event it be desired to control the descent of the platform with the load, the tongue may be reengaged, by means of the tooth 28, with the lifter 24, before the latch 46 is disengaged, and then slowly swung upwardly and rearwardly until the bearing terminals of the shafts 42 are against the stops 15 and 7 and the stops 37 and 38 against said shaft terminals.

When the mechanism is operated to elevate the load and the platform comes into contact with the under surface of the load, there is usually so much frictional resistance that said platform is held stationary while the carriage moves backward on the wheels 14 and 17, but the desired result of 80 elevating the platform and carrying the load up with it is attained just the same as though the carriage were held stationary and the platform moved forwardly as well as upwardly.

The lifter 24 when locked to the tongue 26 serves in the capacity of an equalizer since with said lifter the raising operation, and the lowering operation when controlled by the tongue, are easily and quickly performed under conditions which require the putting forth of an approximately uniform amount of force on the part of the operator, from start to finish, or in other words, the load in being elevated is started slowly and with the minimum expenditure of force, and then as said load continues to rise the same force is in part absorbed as it were in the increased speed with which said load moves, so that such minimum expenditure is continuous, and, inversely, the same thing is true or the same action or kind of action takes place when the load is lowered under the control of the tongue, all of which gives full and complete control into the hands of the operator. This truck need be no higher, when the platform is in low position, than the wheels, and the latter may be of small diameter.

The ease and facility with which the truck, whether loaded or unloaded, can be steered are especially prominent and valuable features of my invention. In backing the truck when loaded, it is not necessary to manipulate the tongue so as to introduce the tooth 28 into the notch 25, although generally said tooth will slip into the same.

What I claim as my invention, and desire to secure by Letters Patent, is—

1. In a truck, relatively movable upper and under sections provided with inclined bearings and racks, and revolute members between said bearings, said members being provided with pinions to intermesh with said racks.

2. In a truck, relatively movable upper and under sections provided with inclined bearings, revoluble members between said bearings, an angular lifter comprising rigid arms one of which is pivotally mounted at its free end, a flexible connection between said upper section and the free end of the other of said lifter arms, and means normally independent of said lifter but adapted 10 to operate the same.
3. In a truck, relatively movable upper and under sections provided with inclined bearings, revoluble members between said bearings, an angular lifter comprising rigid arms one of which is pivotally mounted at its free end, a flexible connection between said upper section and the free end of the other of said lifter arms, and a pivotally-mounted tongue adapted to operate said 15 lifter, such tongue being normally independent of said lifter.
4. In a truck, upper and under mutually reciprocable sections arranged for elevation and depression, an angular lifter pivotally 20 mounted at one end, connections between said upper section and said lifter, a tongue pivotally mounted and longitudinally movable on the same pivot with said lifter and means whereby said tongue may be interlocked with and released from said lifter.
5. The combination, in a truck, of a carriage, a swivel at the front end of said carriage, said swivel being provided with a pivot pin, an angular lifter mounted at one 25 end on said pin, a slotted tongue also mounted on said pin with the latter in the slots, said tongue and lifter having engaging and disengaging means, a platform mounted on said carriage, said carriage and platform being 30 mutually reciprocable and arranged for the elevation and depression of the platform, and connections between said platform and said lifter.
6. The combination, in a truck, of a carriage, a swivel at the front end of said carriage, said swivel being provided with a pivot pin, an angular recessed lifter mounted at one end on said pin, a tongue recessed 35 to receive said lifter and provided with a fixed tooth which is adapted to enter the recess in said lifter, said tongue also being mounted on said pin and slotted to receive the same, a platform mounted on said car- 40
- riage, said carriage and platform being mutually reciprocable and arranged for the elevation and depression of the platform, and connecting means between said platform and said lifter. 45
7. The combination, in a truck, with a carriage, a swivel at the front end of said carriage, and a tongue pivotally attached to said swivel and provided with a dog, of a rising and falling platform mounted on said carriage, means to actuate said platform into its raised position, and a latch to lock said platform when in raised position directly to said carriage, the arrangement of parts being such that said latch may be operated by said dog to release said platform, when said swivel is turned to locate said tongue in position for that purpose. 50
8. The combination, in a truck, of relatively movable, longitudinally, upper and under sections, the upper section also having a rising and falling movement, an angular lifter comprising rigid arms one of which is pivotally mounted at its free end at the forward end of said under section, connecting means between the free end of the other arm of said lifter and said upper 55 section, a tongue mounted to swing and to move longitudinally on the same pivot with said lifter, and means to detachably engage said tongue with said lifter at a point intermediate of the ends thereof. 60
9. The combination, in a truck, of relatively movable, longitudinally, upper and under sections, the upper section also having a rising and falling movement, an angular lifter comprising rigid arms one of which is pivotally mounted at its free end at the forward end of said under section, connecting means between said upper section and the free end of the other arm of said lifter, a tongue mounted to swing and to 65 move longitudinally on the same pivot with said lifter, and means to detachably engage said tongue with said lifter at a point intermediate of the ends thereof said tongue being movable on said pivot to engage and disengage said tongue and lifter. 70
